WEAVING DEVICE

Thomas Boss Congdon and Charles Jacob Long,
New London, Conn., assignors to Celanese Corporation of America, a corporation of Delaware

Application July 22, 1936, Serial No. 91,824

2 Claims. (Cl. 139—207)

This invention relates to a device which is adapted to be attached to a standard cop so that said cop normally used in non-automatic plain looms may, with the device of this invention attached thereto, be used as a quill on shuttle-changing automatic looms.

An object of the invention is the construction of a novel device adapted to be attached to cops so that the use of said cops may be extended, i. e. 10 they may be used in a larger variety of looms. Other objects of the invention will appear from the following detailed description and drawing.

The shuttle and shuttle-changing device of an automatic shuttle-changing loom requires the 15 yarn to be wound upon a special quill having a heavy head circled with ridges that are adapted to be gripped by holders in the shuttle, while many non-automatic looms require the yarn to be wound upon a cop that has merely a flange for a head. 20 The quills are usually made of wood coated with lacquer or enamel and have heavy wire rings circling the head, while the cops are usually made of vulcanized fiber, pressed paper, cardboard, etc., with a thin metal sleeve having a flange pressed 25 over the fiber core to form the head. This invention is concerned with a device adapted to be attached to a core to make it in effect a quill, thus permitting the yarn manufacturer to wind the yarn only on one size cop for both classes of 30 looms. By winding of yarn only on cops not only is the amount of reserve stock required by the manufacturer kept to a minimum, but also a lesser number of winding machines is required on which winding spindles are of only one size. 35 Moreover, by employing in either type of loom a cheaper package core as well as reducing the number of reserve cops, the cost of the said yarn holders is reduced.

In accordance with our invention, we construct 40 a device for attachment to a cop filled with yarn, thus producing a package of yarn that may be substituted for quills in any fabric-forming devices where such yarn packages are normally required. This weaving device or cop attachment 45 is formed with a head having ridges or rings such that it readily fits into suitable gripping devices on shuttles requiring the heavy head found on quills.

In the drawing, wherein any like reference numbers refer to the same or similar elements in the respective views, there is shown a weaving device, or cop attachment, constructed in accordance with our invention. In the drawing:

Fig. 1 is a view partially in section of a cop in 55 operative position with our weaving device,

Fig. 2 is a plan view taken on line 2—2 in Fig. 1 and on a slightly larger scale, of the weaving device with the cop removed,

Fig. 3 is an end view taken on the line 3—3 of Fig. 2, and

Fig. 4 is an elevational view of the head of the weaving device.

The cops normally employed in non-automatic shuttle-changing looms consist of a core 1 made of pressed fiber or other similar material and has 10 a short metallic sleeve 2 pressed over one end of same. The sleeve 2 is formed with a yarn-retaining flange 3 and slippage-preventing grooves 4. The metallic sleeve 2 pressed on to the core 1 is held in place in any suitable manner, such as by 15 punching the walls of the sleeve into the core proper or by the use of lacquers, cements or both. Another type of metallic sleeve 2 may be employed for use with looms having an electric feeler. This type is illustrated but differs only from the above 20 in that the length of the metallic sleeve is longer.

The weaving device, or cop attachment, comprises a cop-supporting member 5 which is in the form of a rod having a diameter slightly less than the inside diameter of the cop and may be made 25 of wood, metal, vulcanized fibre, synthetic plastics or other suitable material. The supporting member is provided with a collar 6 against which the flange 3 of the cop is adapted to abut. The supporting member 5 is also provided with a 30 spring formed of any suitable resilient metal such as copper, steel and the like. This spring is preferably in the form of a disc 8 having a hole therein through which the supporting member 5 may be inserted and two or more fingers 7 and 9, 35 so shaped to extend over the collar 6 and engage the flange on the cop. Two fingers 7 as shown in the drawing or three fingers spaced 120° apart may be employed.

The spring is held between the collar 6 and a 40 head 11. The head 11 may be formed of any suitable material such as an aluminum alloy, wood, artificial resins or the like. Surrounding the head 11 is a metallic sleeve 12 having ridges or rings 13 thereon, adapted for gripping the 45 shuttle of an automatic quill changing loom, positioned in a manner similar to the wire rings on a quill. The ridges 13 may be formed integral with the sleeve 12 or they may be formed of wire rings normally placed upon the wooden quills by 50 forming grooves in the sleeve 12 and placing thereon wire rings. The head 11 is held in place upon the cop-supporting member by means of a rivet pin 14. The head 11 is slotted as at 55 allowing for free lateral movement of the spring 55

fingers 7 and 9. In place of the open slot 15, as shown on the drawing, only the small portion of the sleeve 12 may be cut out leaving at least a part of the rings 13 covering the groove thus formed.

In operation, yarn is wound upon cops and when it is desired to use these cops in an automatic quill-changing loom which requires the yarn to be on quill, the cop-supporting member 5 or weaving device is inserted into the cop until the flange 3 thereof abuts against the collar 6 of the weaving device. When the cop is in this position, the spring fingers 7 and 9 press into the flange on the base of the cop, thus steadyng the 15 cop from wobbling or inclining towards the bottom of the shuttle. The spring fingers also prevent the cop from sliding off the cop-supporting member 5. Each quill-changing automatic loom may be provided with several of these weaving devices or attachments and the operator inserts same in cops and places them in the magazines, or each shuttle may be provided with one of these attachments. Alternatively, when yarn is to be used upon automatic shuttle-changing looms, the 25 manufacturer may attach the weaving device to all the cops to be employed in these looms.

Other modification of the device may be employed. For instance, a shorter assembly may be produced by omitting the collar 6 and counter-boring to offset the difference. In addition, other types of spring means than are shown in the drawing as springs 7 may be employed. Thus, a circular groove may be formed in the inside of sleeve 12 to take a hexagonal piano spring wire or 35 the like. In this modification, as the flange of the cop contacts the spring it contracts, allowing the base of the cop to fit snugly against the

collar 6, or the head 11 if no collar is employed, and then expands, gripping the forward and top edge of the flange 3.

It is to be understood that the foregoing detailed description and drawing is given merely by way of illustration and that many variations may be made therein without departing from the spirit of our invention.

Having described our invention, what we desire to secure by Letters Patent is:

1. A weaving device for adapting the cop type of yarn package to looms normally employing a quill, said device comprising a cop supporting member, said cop supporting member having a recess adapted to receive the flange of a cop tube, 15 a collar in said recess adapted to abut against said flange, said collar being of smaller diameter than said flange and spring means clamped between said collar and said cop supporting member adapted to engage with said flange and to retain it in abutment against said collar.

2. A weaving device for adapting the cop type of yarn package to looms normally employing a quill, said device comprising a cop supporting member, said cop supporting member having a 25 recess adapted to receive the flange of a cop tube, a collar within said recess adapted to abut against said flange, said collar being of smaller diameter than said flange and spring means comprising a plurality of spring fingers clamped at their bases 30 between said collar and said supporting member, said spring fingers being adapted to engage with said flange and retain it in abutment against said collar.
